Primary Examiner — Erich G Herbermann*Assistant Examiner* — David Weir(74) *Attorney, Agent, or Firm* — Mandana Jafarinejad(57) **CLAIM**

The ornamental design for a trash bin sliding rail rack, as shown and described.

DESCRIPTION

FIG. 1 is a perspective right side view of a trash bin sliding rail rack showing my new design;

FIG. 2 is a perspective left side view thereof;

FIG. 3 is a right side view thereof;

FIG. 4 is a left side view thereof;

FIG. 5 is a front side view thereof;

FIG. 6 is a back side view thereof;

FIG. 7 is a top view thereof;

FIG. 8 is a bottom view thereof; and,

FIG. 9 is a partial enlarged view of FIG. 1.

The evenly-dashed broken lines illustrate portions of the trash bin sliding rail rack that form no part of the claimed design. The dash-dot-dash broken lines seen in FIGS. 1 and 9 depict enlargement boundaries and form no part of the claim.
